UNITED STATES PATENT OFFICE.

LAWRENCE C. STEELE, OF PITTSBURGH, PENNSYLVANIA.

SHEET-ALINING MECHANISM.

1,136,059.

Specification of Letters Patent. Patented Apr. 20, 1915.

Application filed November 1, 1913. Serial No. 798,744.

To all whom it may concern:

Be it known that I, LAWRENCE C. STEELE, a resident of Pittsburgh, in the county of Allegheny and State of Pennsylvania, have 5 invented a new and useful Improvement in Sheet-Alining Mechanism, of which the following is a specification.

This invention relates to mechanism for straightening or matching the edges of a 10 sheet or pack of sheets of metal or other material.

The object of the invention is to provide 15 mechanism for straightening or matching the edges of a sheet or pack of sheets, so that the edges of all the sheets will be parallel, or to aline them with devices for operating upon the sheets, such as folding or shearing devices.

While the invention is capable of wide 20 application it is particularly designed for use in connection with doubling mechanism for doubling or folding packs in the manufacture of sheet metal, but may be used in any case where it is desired to straighten a 25 sheet or match the edges of a pack of sheets.

The invention consists, broadly speaking, in side and end matching devices so interconnected and arranged as to simultaneously act upon all four edges of the sheet or 30 pack and simultaneously straighten or match it from all four directions.

In the drawings Figure 1 represents a 35 plan view of a machine embodying the invention, parts of the doubling mechanism being omitted; Fig. 2 is a side elevation thereof; and Fig. 3 is an end elevation.

In the drawings 1 represents a pair of folding or doubling members which are hinged together, and in one position, shown 40 in Fig. 1, form a flat table with its surface at the floor level, the main portion of the machine lying below the floor level. Said members are pivotally supported upon arms 2 which are pivoted to supports 3 on the 45 bed plate 4. The arms 2 are connected to the folding members 1 outwardly from the rod 5 to which they are pivoted, and said members are caused to fold or swing toward and from each other by suitable operating 50 mechanism (not shown) connected to the rod 5 for raising and lowering the same.

6 designates a divider and holding member, which is provided with suitable operating mechanism for causing it to come down 55 on top of and across the middle of the sheet

or pack, just before the doubling members begin to fold toward each other. It acts to hold the pack down upon the doubling members and also as a divider for assisting in folding the pack. The operating mechanism also raises the divider from the pack just before the doubling members reach the limit of their downward movement and before the doubling operation is completed. The doubling mechanism so far described 60 may be of any suitable construction, but preferably is substantially the same as that shown in my prior patent for doubling mechanism granted March 15th, 1910, No. 952,052, and therefore requires no further 65 description.

In folding or doubling sheets or packs, or shearing the same, it is important to aline the sheet or pack upon the table with its edges exactly parallel and transverse to the 70 length of the folding device or to the shearing blade. For this purpose the present machine is provided with both side and end matching devices for matching the sheet or pack in both directions. The side matching 75 devices are indicated at 10. They comprise members 11 having their upper end portions projecting above the level of the table. Said members are pivoted at 13 to carriers 14 having small rollers 15 traveling along 80 a track or runway 16, shown as a bar rigidly secured at its opposite ends to the main frame. The lower end portions 17 of members 11 embrace the track 16 and are made heavier than the upper ends 10 thereof, so 85 that normally the latter always project above the table. The carriers 14 are provided with side pins or projections 18 working in slots in the arms of a yoke 20 embracing said carriers and which yokes are 90 carried on the upper ends of levers 21.

Any number of side matching devices 95 may be used, in accordance with the size of the machine and the length of the pack or sheet to be doubled thereon. In the machine shown there are four matching devices, two on each side of the sheet. The four levers 21 carrying the matching devices are fixedly secured to shafts 22 journaled in projections 23 on the supports 3. 100 Suitable means is provided for causing the side matching devices along both edges of the sheet or pack to operate in unison. In Fig. 3 this means comprises a link 24 pivotally connected at one end, as at 25, to an 105 110

2
 arm 26 on one of the levers 21, and at its other end, as at 27, to an arm 28 rigidly connected to the shaft 22 carrying the other pair of levers. Pivots 25 and 27 are located 5 at exactly the same distance from their respective shafts 22, but one is above and one is below the same. Consequently, when one lever 21 is swung in one direction by its shaft 22 the levers on the other shaft 22 10 swing in the opposite direction. The connection is also a positive one so that movement of either shaft 22 or of any lever moves all four of the side matching devices.

The end matching devices are indicated 15 at 30, said devices comprising pivoted members having heavy lower end portions 31 and upper end portions 32 projecting above the table level. One of said members is carried by a lever 34 rigidly connected to a 20 shaft 35 journaled in lugs 36 on the main frame. The other member 30 is carried on the upper end of a lever 37 rotatably mounted on a shaft 38 journaled in lugs on the frame. Shaft 38 has rigidly secured 25 thereto a lever 39 provided at its upper end with a yoke 40, the arms of which are provided with longitudinal slots 41 to receive a pin 42 which may be placed in any one of the notches 43 in a toothed segment 44 rigidly attached to or forming a part of lever 37.

The levers carrying the end matching devices are connected to operate in unison in the same manner as the levers carrying the 35 side matching devices. As shown the connecting means therebetween comprises a link 45 pivotally connected at one end, as at 46, to an arm 47 rigidly secured to the shaft 35, and at its other end, as at 48, to an arm 49 40 rigidly attached to shaft 38. The pivots 46 and 48 are located at the same distance from their respective shafts 35 and 38, but one of said pivots is above its shaft and the other below, so that the levers 34 and 37 always 45 move in opposite directions.

The side and end matching devices may be operated independently of each other, so that the sheet or pack can be straightened in either direction alone, or in both separately. Preferably however, means is provided whereby the sheet or pack can be straightened in both directions simultaneously, and by the operation of a single device, such as an operating handle. As shown 50 55 the operating lever or handle 50, which projects above the floor level, is journaled upon one of the shafts carrying the levers to which the matching devices are connected, such as the shaft 35. Connected to said 60 lever, as by link 51, is a sheave or pulley 52 around which passes a flexible operating member 53, such as a band, belt, chain, cable, or the like. One end portion or strand 53^a of the member 53 is connected to operate the 65 side matching devices, while the other end

or strand 53^b is connected to operate the end matching devices. In the arrangement shown, where lever 50 is pivoted on the shaft 35 one end 53^b of the member 53 passes directly across the machine, and may be connected directly to arm 39, but is shown as connected to an arm 54, rigid with the shaft 38. The other end portion 53^a of the member 53 passes around a sheave or pulley 55 and then in a direction at right angles to itself, and is connected directly to one of the levers 21.

In use of the machine the sheet or pack is laid or placed on the table in substantially the proper position. If it is a single sheet, 80 it may be slightly out of line, so that if folded at its middle the two layers would not be superposed directly upon each other. If it is a pack the separate sheets may not have their sheets parallel, and it may also be 85 askew as a whole upon the table. The lever 50 is now swung to the left in Fig. 2 thereby placing both end portions 53^a, 53^b of the cable 53 under tension. One end pulls on arm 54 and swings shaft 38 to the left in 90 Fig. 2. Shafts 38 and 35 are interconnected by links 45 and levers 39 and 34 move toward each other, lever 39 dragging lever 37 after it. The end matching devices strike the ends of the pack and straighten it up 95 endwise. If it has been placed a little too near one end of the table it will be shifted endwise thereon to the center of the table by the end matching device which strikes it first.

In some cases one end of the sheet or pack 100 has a rough edge, which may curve either inwardly or outwardly toward the center of the sheet. The adjustment between levers 39 and 37 before described allows one of the 105 end matching devices to be adjusted with reference to the other to compensate for unevenness, so that advantage can be taken of all perfect portions of the sheet or pack without undue waste of material in the 110 shearing or trimming operation. The other end portion 53^a of the cable 53, which passes around the sheave or pulley 55, exerts tension on one of the levers 21. The two pairs of levers 21, on the oppositely disposed 115 shafts 22, are interconnected by link 24 so that all of the side matching devices move simultaneously toward the center of the machine. The sheet or pack is consequently straightened sidewise, so that its side edges 120 are normal to the divider or folding device 6, and when the latter comes down on the sheet or pack the two end portions thereof will be superposed exactly on each other.

It will be observed that a sheet or pack is 125 matched or straightened on the table in both directions irrespective of its relative dimensions in different directions. This is due to the flexible character of the operating mechanism for simultaneously moving both 130

the end and side matching devices and the fact that the set of matching devices which first engages the sheet becomes a fulcrum or fixed point of purchase for further movement of the operating member to adjust the other set of matching devices and straighten the sheet in the other direction. Lever 50 is pulled over until all of the matching devices have engaged the edges of the sheet, at

5 which time the sheet lies centrally disposed over the folding members with its edges parallel and normal to the divider 6. If the sheet is small, lever 50 must be swung farther in the operating directions than if the

10 sheet is large.

The heavy lower end portions 31 of the end matching devices 30 are on the sides of the levers 34 and 37, away from the center of the machine. Consequently, when the 20 levers move toward each other the matching devices 30 become in effect rigid portions of said levers with their inner edges substantially vertical or normal to the table surface, when the levers move over their normal operating range. The projecting upper ends 25 of the matching devices 30, however, can be swung toward the center of the machine, thereby enabling a sheet or pack to be slid upon the table from either end without lifting it over the matching device. The latter merely sinks into the table and when the sheet has passed thereby, the weighted lower end causes it to again rise to normal position. The same is true of the side matching devices, the lower ends of which engage the outer faces of the carriers 14, but the upper ends of which can be swung toward the center of the machine by a sheet or pack passing thereover.

40 The construction described is quite simple and reduces the number of operating levers on the machine. All of the matching devices, both side and end, are operated by a single lever to match the pack perfectly in both directions irrespective of its size. Moreover, the relative adjustment between the end matching devices prevents undue waste of metal in the shearing operation. The invention can be used alone or can be 45 applied to any type of folding or doubling machine, not being restricted to that shown or described. It can also be applied to shearing machines for straightening the sheet or pack with respect to the shears.

55 What I claim is:

1. In a machine for operating upon sheets, the combination with a table, of two sets of matching devices arranged to straighten a sheet upon the table in two directions, each set comprising members movable toward and from each other, and a single flexible means for operating all of said members, the members of one set being adjustable with reference to each other.

65 2. In a machine for operating upon sheets,

the combination with a table, of two sets of matching devices arranged to straighten a sheet upon the table in two directions, each set comprising interconnected members movable toward and from each other, and flexible means having portions connected to both sets of members and arranged when operated to simultaneously move all of said members toward the center of the table.

3. In a machine for operating upon sheets, the combination with a table, of two sets of matching devices arranged to straighten a sheet upon the table in two directions, each set comprising interconnected members movable toward and from each other, a movable operating member carrying a sheave, and a flexible member passing over said sheave and having portions connected to both of said sets of devices for adjusting the same.

4. In a machine for operating upon sheets, the combination with a table, of matching devices movable toward and from each other for adjusting the sheet upon the table, pivoted levers carrying said members, and connections between said levers arranged so that they oscillate toward and from each other, one of said levers being adjustable around its pivot for adjusting the matching devices with reference to each other.

5. In a machine for operating upon sheets, the combination with a table, of a plurality of sets of matching devices arranged to straighten a sheet upon the table in different directions, each set comprising interconnected members movable toward and from each other, a movable operating member, and a flexible member having a loop or fold connected to said operating member, portions thereof being connected to said sets of matching devices for operating the same.

6. In a machine for operating upon sheets, means for straightening a sheet or pack, comprising a side matching device, an end matching device, a single movable operating member, and connections between said member and said devices, said connections being so arranged that after one of said devices engages the sheet or pack it becomes a fulcrum for the operating member to further adjust the other of said devices.

7. In a machine for operating upon sheets, means for straightening a sheet or pack, comprising a side matching device, an end matching device, a single movable operating member, and connections between said member and said devices, said connections being so constructed and arranged that after either of said devices engages the sheet or pack it becomes a fulcrum for the operating member to further adjust the other of said devices.

8. In a machine for operating upon sheets, means for straightening a sheet or pack, comprising a set of inter-connected side matching devices, a set of inter-connected

70

end matching devices, a single movable operating member, and connections between said member and said sets of matching devices, said connections being so arranged 5 that after the matching devices of one set engage the sheet they become a fulcrum for the operating member to further adjust the other of said matching devices.

9. In a machine for operating upon sheets, 10 means for straightening a sheet or pack, comprising a set of inter-connected side matching devices, a set of inter-connected end matching devices, a single movable operating member, and connections between 15 said member and said sets of matching devices, said connections being so arranged that after the matching devices of either set engage the sheet or pack they become a ful-

crum for the operating member to further adjust the other set of matching devices. 20

10. In a machine for operating upon sheets, the combination with a table, of two sets of matching devices arranged to straighten a sheet upon the table in two directions, each set comprising members movable toward and from each other in unison, and a single flexible member connected to both sets of matching devices for operating 25 all of said members.

In testimony whereof, I have hereunto 30 set my hand.

LAWRENCE C. STEELE.
